UNITED STATES PATENT OFFICE.

SIMEON S. JACKSON, OF BOSTON, MASSACHUSETTS, ASSIGNOR TO THE STANWICH COMPANY, OF READVILLE, MASSACHUSETTS, A CORPORATION OF NEW JERSEY.

LOOM.

1,100,886.

Specification of Letters Patent. Patented June 25, 1912.

Application filed September 25, 1912. Serial No. 722,282.

To all whom it may concern:

Be it known that I, SIMEON S. JACKSON, a subject of Great Britain, residing at Readville, Boston, in the county of Suffolk, State 5 of Massachusetts, have invented a certain new and useful Improvement in Looms, of which the following is a specification, reference being had therein to the accompanying drawings.

10 Certain kinds of looms are equipped with mechanisms for the performance of special functions, normally non-acting but arranged to be called into action at intervals. Automatic weft-replenishing looms and the weft-replenishing instrumentalities thereof may be instanced. In some cases the said mechanisms are tripped into action automatically by means of pattern devices or other analogous controlling means; in others, by 20 means of weft-detector devices.

The invention comprises novel means for safe-guarding against the special mechanism employed in a loom being tripped into action at an improper time by mischance or 25 accident, or through being meddled with.

The invention is shown herein applied in connection with certain of the parts of a weft-replenishing loom of the general character of that shown and described in U. S. 30 Letters Patent No. 945,722, dated January 4, 1910, and as embodied in novel safety-lock devices for preventing the change-shaft of such loom from being clutched to the change-mechanism drive at an improper time.

35 In the drawings.—Figure 1 is a side elevation of the driving side of the loom just referred to. Fig. 2 is a front elevation of certain of the parts of Fig. 1, on an enlarged scale. Figs. 3 and 4 are detailed views on 40 enlarged scale showing different positions of the safety-lock devices.

Having reference to the drawings, which include only such parts of the loom of Patent No. 945,722 as appear necessary to 45 assist in arriving at an understanding of the relations and nature of the invention, it is noted that in so far as the parts correspond with those shown and described in the said patent they are given the same reference characters as in the latter.

The side-frame at the driving-end of the loom is marked 1 in the different views, the breast-beam is marked 2 in Fig. 2, and the crankshaft is marked 3 in Fig. 1. At 7 in

Fig. 1 is the loose band-pulley of the loom, so rotated continuously by means of the driving-band 8, and formed as one of the members of the clutch by which driving power is communicated to the crankshaft to operate the weaving instrumentalities. At 10 is the loom-shuttle handle, it having a pin 11 pivoted to it by a pivot 19; the upper end of a pin 19 which is slotted at 191, Fig. 1, carries a pin 123 projecting from shuttle-slide 122 for said clutch. At 151 is the bracket 15 carrying a pin 162 which projects over the shuttle-slide 122 so that the shuttle-slide is lifted to set off the brake when the safety-lever is lifted. At 411, Fig. 1, and 412, Fig. 2, is a tripping rock-shaft, mounted in a bearing 412, Fig. 2, in front of the breast-beam, and provided with an upwardly extending arm 41 by means of which it is operated from the weft-detector device, and with a slot 42 which through engagement with a cam-shaft on shuttle-handle 20 trips the latter to arrest the weaving instrumentalities. At 21 is the arm projecting from the tripping rock-shaft, whereby the change-mechanism is tripped into action simultaneously with the said arrest.

The change-shaft forming a part of the change-mechanism of Letters Patent No. 945,722, is partly shown at 25. The change-mechanism drive includes the continuously-rotating loose worm-gear 25 driven from the loose band-pulley 7, and the clutch devices, described above, for clutching said worm-gear to the change-shaft when the latter is required to rotate. The said 30 drive and the clutch devices as shown are substantially as in Patent No. 945,722, but may be varied as desired in practice. At 257 is a controlling-lever forming an element of the said clutch-devices, and at 260 is a latch by which the clutch-controlling lever 257 is held in its working position shown in Fig. 2 to uncouple the worm-gear 25 from the change-shaft. In showing one application of the invention I have employed a latch different from that of Patent No. 945,722 and have combined it differently with the clutch-controlling lever. In most cases, however, the form, etc., of the latch are not material, so far as the invention is concerned. As in the said patent, the latch in this instance also is integrally combined with the weft-detector device.

through connection to arm 43 of the tripping rockshaft 411, so that when the time for represhing has arrived, and such devices act to throw off the loom-shipper and apply the brake to arrest the weaving instrumentalities, they also operate the latch to release the clutch-operating lever so as to permit the worm-gear 75 to be clutched to the change-shaft, to rotate the latter.

10 My novel safety-lock devices herein coact with the latch and are combined operatively with the shipper-handle 20, Figs. 1 and 2, so that the latch is locked while the shipper-handle is "on" and the loom in full weaving 15 operation, and also while the shipper-handle is "off" and the loom at rest, to guard against the change-shaft being started-up at either of such times. But they are so contrivated and combined that in the intermediate 20 position of the shipper-handle the latch is unlocked, affording an opportunity for the automatic tripping of the change-shaft clutch to start-up the change-shaft just as the weaving instrumentalities come to rest.

25 Briefly described, the means shown for driving loose worm-gear 75 from loose band-pulley 7 comprises the bevel-gear 710 fast with said band-pulley, bevel-pinion 72 meshing with said bevel-gear, inclined shaft 73 upon the upper end of which the said bevel pion is fast, and worm 14 fast on the lower end of said inclined shaft and meshing with the said worm-gear.

The clutch-devices shown for clutching the 30 continuously-rotating loose worm-gear to change-shaft 7 comprise clutch-openings or holes 751, 751, etc., Figs. 1, 3, 4, in the worm-gear, clutch-lever 252, Figs. 2, 3, 4, pivoted at 253, 253, upon the disk 251 fast upon the 35 change-shaft, said lever provided with a tooth which works through a hole or opening in said disk, and spring 256 which acts upon said clutch-lever with a tendency to swing it upon its pivots, and, when the 40 clutch-lever is permitted to swing, causes the clutch-tooth thereof to enter a clutch-opening or hole 751 so as to clutch the change-shaft to the worm-gear. Clutch-controlling lever 257 is mounted pivotally upon fixed 45 stand 5, Fig. 2. As heretofore, it is provided with a cam to co-act with the tail of clutch-lever 252, so that as the change-shaft completes a rotation and the said tail makes contact with the face of said cam the latter 50 shall act to turn the clutch-lever upon its pivots 253, 253, so as to withdraw the clutch-tooth from engagement with the worm-gear and permit the change-shaft to stand at rest, with the clutch-lever held in 55 its retracted position by the controlling lever.

The latch *c* is mounted upon the pivot *c'* carried by the fixed stand *d*, as shown best in Figs. 3 and 4. Its shoulder is arranged to 60 engage with an arm *e* with which the clutch-

controlling lever is provided. When such shoulder is thus engaged the latch holds clutch-controlling lever 257 in its working position shown in Fig. 2, to unclutch the worm-gear 75 from the change-shaft so that the latter shall stand at rest. A contracting spiral spring *f* tends to draw the latch forward and to keep it engaged with the said arm, as in Figs. 1, 2 and 3.

The connection between the latch and the weft-detector devices comprises, in this instance, a connector *g*, which is connected at its upper end to the arm 43 fixed on the tripping rockshaft 411. The connection is established by means of a collar *g*¹¹ on the upper portion of the connector *g*, the collar and connector being securely fixed together by means of a clamping-screw *g*¹² and the collar being pivotally engaged with the said arm 43. The connector *g* is in the form of a rod or wire having its lower end-portion formed into a loop *g'*, Figs. 3 and 4, receiving a pin *h* projecting from an arm *i* in connection with the latch *c*. When arm 41 is swung forward by the action of the weft-detector devices, thereby rocking tripping rockshaft 411 so as to swing arm 43 upward, the upward movement of connector *g* causes the latch *c* (if unlocked) to be swung out of engagement with arm *e*, thereby releasing the clutch-controlling lever so that the latter yields to permit clutch-lever 252 to be actuated by its spring 256 so as to clutch the constantly-running worm-gear 75 to the change-shaft. Connector *g* may be adjusted 95 up or down relative to collar *g*¹¹ to regulate the action of the same and of latch *c*.

As soon as the tail of the clutch-lever passes away from the cam-face of the clutch-controlling lever 257, the weight of arm *e* of the latter causes said lever 257 to swing into its working position again, and latch *c* is caused by spring *f* to snap into engagement with arm *e*, thus locking the lever in readiness to act upon the tail of clutch-lever 252 100 as it comes around at the close of a rotation of the change-shaft.

A feature of the invention is a provision for yielding to prevent the parts from being strained or broken in case the arm 41 should 115 be swung forward at a time when the latch *c* is locked against movement. In this instance the arm *i* is made capable of yielding. It is shown as mounted pivotally at *k* upon an arm *m* forming a rigid part of latch *c*, and as being held normally in contact with a fixed stop *n* upon arm *m* by means of a contracting spiral spring *o*, one end of which is connected to a projecting part of arm *i* and the other to a projecting part of the carrying-arm *m*. Should the connector *g* be moved upward at a time when the latch *c* is locked and incapable of moving, the spring *f* will yield to permit arm *i* to turn upon pivot *k* connecting it with the arm *m*. 120 125 130

Referring now to the safety-lock devices in which the invention mainly resides,—As here embodied, a lock for the latch *c* is shown at *p*, Figs. 1, 3 and 4. It consists of 5 an arm which is pivoted at *p'* upon a rearward extension of stand *d*, with capacity for vertical swinging movement, the limits of which are fixed by stops *p*², *p*³, upon stand *d*. The forward end of said arm is constructed 10 for engagement with a portion of latch *c*. When the latch is forward in engagement with arm *e* of the clutch-controlling lever 257, as in Figs. 1 and 3, and the lock itself is 15 in its lowest position in engagement with the latch, as in said figures the lock prevents the latch from disengaging from arm *e*. Consequently the clutch-controlling lever 257 is held locked in its working position and the change-shaft remains at rest. When 20 the lock is raised out of its working position, the latch is thereby unlocked so that it is rendered capable of being disengaged from arm *e* of the clutch-controlling lever to allow the clutch-devices to clutch the change-shaft to 25 the constantly revolving worm-gear 75.

The action of the lock is controlled by a lock-controller *q*, which in this instance is constituted by a rocking-cam pivoted at *q'*, upon stand *d*, and engaging by its cam-face 30 with the underside of a pin *p*³ carried by lock *p*. The gravity of the lock, aided by the tension of a spring if deemed advisable, keeps the pin *p*³ in contact with the said cam-face, so that the shape of the latter determines 35 the position of the lock. The cam-face has a prominence which is located intermediate two depressions. When either depression is presented to the pin *p*³ the lock is free to assume or retain its working position 40 occupied in Fig. 3. As the controller is rocked from one extreme position to the other, the projection in passing the pin *p*³ raises the lock, thereby disengaging it from the latch. As the projection passes out of 45 engagement with pin *p*³ the lock is allowed to drop back toward its working position.

The lock-controller *q* is connected with the shipper-handle 20 by means of a connector *q*², the upper end of which is connected to 50 the link 19. The connection of connector *q*² with link 19 is by means of a collar *q*²¹ on the connector, secured adjustably thereon by means of a clamp-screw *q*²² and having the lower end of link 19 pivotally engaged therewith. When the shipper-handle is moved 55 into its "on" position occupied by it in Fig. 1, the movement of link 19 upward not only moves the shipper-lever 122 and brake-lever 161 to start the weaving instrumentalities, but serves through connector *q*² to rock the lock-controller *q* into the position occupied 60 by it in Fig. 3. In such position of the lock-controller the front depression of its cam-face is presented to the pin *p*³ and permits 65 the lock to assume its locking position, so that

the latch cannot be jarred, by the action of the loom-mechanism in weaving, or knocked, or brushed out of engagement with arm *e*. Consequently release of the clutch-controlling lever 257 by accident or mischance, and 70 resulting clutching of the change-shaft to the constantly rotating worm-gear 75, cannot occur. When the shipper-handle is thrown off, the movement of pivot 192 lowers link 19 and connector *q*², and, in addition 75 to permitting the shipper-lever and brake-lever to act to arrest the weaving instrumentalities, rocks the lock-controller *q* from its position in Fig. 3 to that occupied by it in Fig. 4. As the lock-controller is thus rocked, 80 its prominence raises the lock momentarily, the lock being left free to drop again by the depression which is then presented to pin *p*³. During the momentary elevation of the lock the latch is unlocked, and at this time it is 85 capable of being disengaged from the clutch-controlling lever by the action of the weft-detector devices. If it is not disengaged while the lock is elevated, it is locked again by the immediately following descent of the 90 lock, and it continues locked during the stoppage of the loom until the weaver restarts the latter by throwing on the shipper-handle. Consequently he may work around the loom, and operate the same by hand, without danger 95 of accidentally starting-up the change-shaft. In brief, therefore, the lock holds the latch locked while the loom-shipper is "on" and also while it is "off," that is to say at all times except during an intermediate portion 100 of the movement of the loom-shipper.

The loop or slot *g'* in the lower end of the connector *g* is vertically elongated so that it permits lost-motion between the said connector and pin *h*. Consequently, when the tripping rock-shaft is rocked the toe 46 thereof acts to throw off the shipper-handle before the lower end-wall of said loop or slot engages with the said pin *h*. This gives a sufficient lead to the lock-controller *q* to enable 110 its prominence to lift the lock in time to permit withdrawal of the latch by movement transmitted through connector *g*.

The latch resets itself automatically as soon as controlling lever 257 resumes its 115 working position, and the lock resets itself automatically as soon as the latch has reset itself.

I do not claim broadly herein devices for tripping the loom-shipper and also tripping 120 the change-shaft drive into action to operate the change-shaft, and a lock operatively controlled by said loom-shipper preventing establishment of such relations at an improper time; or a change-shaft drive including 125 a clutch and clutch-controlling means, loom-shipper, and devices by which the loom-shipper is tripped, and by which also said clutch is tripped to establish driving relations between said drive and the 130

- change-shaft, having combined therewith a lock for said clutch-controlling means, itself operatively controlled by said loom-shipper, preventing establishment of such relations at an improper time, inasmuch as I have made broad claim thereto in my co-pending application for patent for improvements in looms filed Aug. 28, 1912, Serial No. 717,444.
10. What is claimed is,—
1. In a loom, the combination with a change-mechanism drive, a latch for latching said drive out of driving relations with the change-mechanism, a controller-member, devices for tripping said controller-member and said latch, and a lock for said latch, of a lock-controller operatively controlled by said controller-member, providing for locking the latch to thereby lock the drive out of such relations while the controller-member occupies its respective opposite positions, and for unlocking it temporarily during movement of the said member when tripped, to thereby permit the latch to be tripped.
  2. In a loom, the combination with a change-mechanism drive, a latch for latching said drive out of driving relations with the change-mechanism, a loom-shipper, devices for tripping said loom-shipper, and said latch, and a lock for said latch, of a lock-controller operatively controlled by said loom-shipper, providing for locking the latch to thereby lock the drive out of the said relations while the loom is running and also while standing idle, and for unlocking it temporarily during movement of the loom-shipper, when tripped, from on to off.
  3. In a loom, the combination with a change-mechanism drive, a latch for latching said drive out of driving relations with the change-mechanism, a controller-member, weft-detector-actuated devices for tripping said controller-member and said latch, and a lock for said latch, of a lock-controller operatively controlled by said controller-member, providing for locking the latch to thereby lock the drive out of such relations while the controller-member occupies its respective opposite positions, and for unlocking it temporarily during movement of the said member when tripped to thereby permit the latch to be tripped.
  4. In a loom, the combination with a change-mechanism drive, a latch for latching said drive out of driving relations with the change-mechanism, a loom-shipper, weft-detector-actuated devices for tripping said loom-shipper, and said latch, and a lock for said latch, of a lock-controller operatively controlled by said loom-shipper, providing for locking the latch to thereby lock the drive out of the said relations while the loom is running and also while standing idle, and for unlocking it temporarily during movement of the
- rarely during movement of the loom-shipper, when tripped, from on to off.
5. In a loom, the combination with a change-mechanism clutch, a latch for latching the said clutch out of action, a controller-member, devices for tripping said controller-member and said latch, and a lock for said latch, of a lock-controller operatively controlled by said controller-member, providing for locking the latch to thereby lock the clutch out of action while the controller-member occupies respective opposite positions, and for unlocking it temporarily during movement of the said member when tripped, to thereby permit the latch to be tripped by the said devices.
6. In a loom, the combination with a change-mechanism clutch, a latch for latching the said clutch out of action, a loom-shipper, devices for tripping said loom-shipper and said latch, and a lock for said latch, of a lock-controller operatively controlled by said loom-shipper, providing for locking the latch to thereby lock the clutch out of action while the loom is running and also while standing idle, and for unlocking it temporarily during movement of the loom-shipper when tripped, to thereby permit the latch to be tripped by the said devices.
7. In a loom, the combination with a change-mechanism clutch, a latch for latching the said clutch out of action, a controller-member, devices for tripping said controller-member and said latch, and a lock engaging said latch, of a controller-cam operatively engaging said lock and actuating it to provide for locking the latch to thereby lock the clutch out of action while the controller-member occupies respective opposite positions, and for unlocking it temporarily during movement of the said member when tripped, to thereby permit the latch to be tripped by the said devices.
8. In a loom, the combination with a change-mechanism clutch, a latch for latching the said clutch out of action, a loom-shipper, devices for tripping said loom-shipper and said latch, and a lock engaging said latch, of a controller-cam operatively engaging said lock and actuating it to provide for locking the latch to thereby lock the clutch out of action while the loom is running and also while standing idle, and for unlocking it temporarily during movement of the loom-shipper when tripped, to thereby permit the latch to be tripped by the said devices.
9. In a loom, the combination with a change-mechanism clutch, a latch for latching the said clutch out of action, a loom-shipper, and a lock operatively controlled by the loom-shipper and engaging said latch, of devices for tripping said loom-shipper and said latch, having provisions for yield-

ing to obviate injury when movement thereof is resisted by the latch continuing locked.

10. In a loom, in combination, a change-mechanism clutch, a latch for latching the said clutch out of action, having a yieldable

loom-shipper and said latch, operating the latter by means of said yielding arm.

In testimony whereof I affix my signature in presence of two witnesses.

SIMEON S. JACKSON.
